UNITED STATES PATENT OFFICE.

CHARLES THOMAS BROCK SANGSTER, OF BIRMINGHAM, ENGLAND.

DESIGN FOR A BICYCLE-FRAME.

SPECIFICATION forming part of Design No. 34,255, dated March 19, 1901.

Application filed February 21, 1901. Serial No. 48,379. Term of patent 3½ years.

To all whom it may concern:

Be it known that I, CHARLES THOMAS BROCK SANGSTER, general manager of The Cycle Components Manufacturing Company, Limited, a 5 subject of the King of Great Britain, residing at Bournbrook, Birmingham, England, have invented and produced a new and original Design for a Bicycle-Frame, of which the following is a specification.

The drawing represents a perspective view of my new and original design for a bicycle-frame.

The leading or material feature of my design consists in the crossing diagonal stay-tubes *a* and *b*, disposed between the head *c* 15 and the upper part of the seat-tube *d*, and the dual backstays *e* and *f*, the former extend-

ing, as usual, from the summit of the seat-tube to the outer ends *g'* of the chain-stays *g*, and the latter directed from the seat-tube 20 at its junction with the stay *b* to the stay ends *g'*.

Having described my invention, what I claim as new, and desire to secure by Letters Patent, is—

The design for a bicycle-frame, as herein described and shown.

In testimony whereof I have hereunto set my hand in presence of two subscribing witnesses.

CHARLES THOMAS BROCK SANGSTER.
Witnesses:

AGNES ROSE,
ARTHUR T. SADLER.
